DOOR LOCK

James D. Leslie, Detroit, and Clyde H. Schamel, Royal Oak, Mich., assignors to General Motors Corporation, Detroit, Mich., a corporation of Delaware

Application November 28, 1947, Serial No. 788,534

12 Claims. (Cl. 292—229)

1

This invention relates to a door lock for an automotive vehicle.

It is common practice in the present day automobile to seal the door in the door opening by means of an elastic rubber strip which extends completely around the edge of the door. This rubber door seal is compressed or distorted between the door and the portion of the vehicle body defining the door opening when the door is closed. The hinged door is held closed by interengagement of the latch bolt and the striker plate. The outward force or thrust exerted by the compressed door seal is considerable and usually runs in the neighborhood of about one hundred pounds but may be more or less. Where the sealing pressure of the door is considerable, the conventional sliding bolt type latch requires considerable force to retract the same out of interengagement with the striker plate and therefore under such conditions the sliding bolt type lock is not suitable for operation by a push button but requires a handle or the lever type.

It is an object of this invention to produce a door lock for an automotive vehicle which operates easily and virtually independently of the door sealing pressure.

The invention contemplates a door lock for an automotive vehicle wherein the lock bolt can be readily and easily released out of interengagement with the striker by, e. g., a finger actuated push button or trigger or pull-out mechanism virtually irrespective of the door sealing pressure and even when sealing pressures are used which are considerably higher than practically necessary for effecting a weather-proof seal between the door and the portion of the vehicle body defining the door opening.

This purpose is accomplished by providing the door lock with a roller type lock bolt which is maintained in interengagement with the striker plate by a multiplier lever and detent lever, the multiplier lever having considerable mechanical advantage over the bolt and the detent lever being disengageable from the multiplier lever by motion transversely of the direction of application of a force of the multiplying lever on the detent so that release of the detent can be accomplished with only a fraction of the force exerted by the multiplier lever upon the detent lever.

Fig. 1 is a fragmentary inside view of a vehicle door and body with our lock holding the door closed.

Fig. 2 is a section along the line 2—2 of Fig. 1.

Fig. 3 is a section along the line 3—3 of Fig. 1 showing the outside stationary door handle and push button for releasing the latch bolt.

2

Fig. 4 is a detail similar to Fig. 3 showing the push button in bolt releasing position.

Fig. 5 is an elevation of our lock showing the position of the various parts when the bolt is interengaged with the striker and the lock is unlocked so that the bolt can be released by actuation of the outside push button or the inside control.

Fig. 6 is a section along the line 6—6 of Fig. 5.

10 Fig. 7 is a section along the line 7—7 of Fig. 5.

Fig. 8 is a detail of the upper right hand portion of the lock shown in Fig. 5.

15 Fig. 9 is an elevation of our lock showing the position of the slide bar when the outside push button is ineffective to retract the detent lever.

Fig. 10 is a section along the line 10—10 of Fig. 9.

Fig. 11 is an elevation of the lock showing the position of the parts when the bolt is disengaged from the striker.

Fig. 12 is a section along the line 12—12 of Fig. 11.

20 Figs. 13, 14 and 15 are detail showings of individual parts of the lock.

Fig. 16 is a fragmentary elevation of the lock with the bolt in safety position.

Fig. 17 is an enlarged detail showing of the multiplier lever and detent lever when the lock bolt is fully engaged with the striker.

25 Fig. 18 is an enlarged fragmentary detail of the multiplier lever and detent lever in safety position.

Fig. 19 is an elevation showing a modified form of our lock with the bolt disengaged from the keeper.

Fig. 20 is an elevation of the modified form of lock showing the position of the parts when the bolt is fully interengaged with the keeper.

Fig. 21 and 22 are detail showings of individual parts of our modified form of lock.

Fig. 23 is a fragmentary elevation of our modified form of lock showing the lock bolt in safety position.

20 Figs. 24, 25 and 26 are sections taken respectively along the lines 24—24, 25—25 and 26—26 of Fig. 20.

Fig. 27 is a top plan view of the inside control push button arrangement which can be used with either form of the invention.

50 Referring more particularly to the drawings there is shown a portion of an automobile body having a door 2 which is hinged in the conventional and well known manner. A striker 3 is secured by screws on the body pillar 4. The outer face of the pillar is designated 5. Striker 3 has a dog-leg form of channel 6 having a portion 7 which extends inwardly from the outside of the

body and slightly upwardly and a portion 8 which extends upwardly at an acute angle to the vertical. The lower face of the channel is designated 9 and the upper face 10.

The lock bolt takes the form of a lever 11 pivoted to the lock frame 12 by pin 13 which is riveted over at each end. The body of the bolt is preferably a stamping and the head 14 is made of a rolled section or die cast material and secured to the body by rivets 15. A roller 16 is journalled on the end 17 of the bolt head and retained thereon by washer 18 and the upset portion 19 of the bolt head. Flange 41 of lock frame 12 is provided with a vertical slot 42 in which the bolt head 14 swings vertically.

A multiplier lever 20 is pivotally mounted upon lock frame 12 by rivet pin 21. Lever 20 is provided with a radially extending recess 22 which slidably receives the enlarged cylindrical head 23 of rivet 15. Lever 20 is provided with teeth 24 and 25 each of which are arranged to interengage tooth 26 of detent lever 27 which is pivoted on lock frame 12 by pin 28. A convolute spring 29 has one arm 30 anchored to bolt 11 as at 31 and the other arm 32 anchored to detent lever 27 as at 33 (Fig. 5). As viewed in Fig. 5, spring 29 urges both bolt 11 and detent lever 27 downwardly or in a clockwise direction. The use of spring 29 for swinging bolt 11 downwardly is preferred but optional because bolt 11 will swing downwardly of its own weight whenever detent lever 27 is disengaged from multiplier lever 20.

Referring to Fig. 17, it will be seen that multiplier lever 20 swings about the center 34 of pin 21 as a center. The respective faces 35 and 36 of teeth 24 and 25 are positioned radially of center 34 exactly the same distance. It is also evident that the lever arms extending between axis 34 and faces 35 and 36 respectively are each considerably longer than the lever arm extending between axis 34 and the line of contact 37 between the lower face 38 of recess 22 and pin 23.

Detent lever 27, which swings about the center 39 of pin 28 as an axis, has the face 40 of tooth 26 formed as a true arc, the center of which is axis 39. Similarly face 36 of tooth 25 is an arc of a true circle, the center of which is axis 39 when faces 36 and 40 are interengaged or in contact with each other. In other words, faces 36 and 40 are arcs having equal radii and a common center. Arcuate face 36 is tangent at its midpoint to a radial straight line passing through axis 34 and the same is true of arcuate face 35 of tooth 24. Thus, when teeth 25 and 26 are interengaged a counterclockwise movement of detent lever 27 will not swing multiplier lever 20 about its axis and consequently only sufficient force need be applied to detent lever 27 to overcome the friction between faces 36 and 40. In other words, detent lever 27 can be released without movement of lever 20 because arcuate faces 36 and 40 have a common center 39 and therefore in releasing detent lever 27 it is not necessary to overcome any force except that tangentially exerted by face 36 against face 40 at the area of contact. Thus, because a large proportion of the door seal force is absorbed in friction, bolt 11 can be released very easily and virtually irrespective of the sealing pressure exerted against the bolt.

By way of illustration: When the door is fully closed and the lock bolt is in raised position, shown in Fig. 5, if the rubber door seals exert eighty pounds pressure against the bolt head 16, then the pressure exerted by pin 23 at line 37

on multiplying lever 20 will be about sixty pounds (about thirty-eight pounds being absorbed in friction of the bolt 11 and its attaching parts against the lock case 12, and by the friction of pin 23 in the slot 38) and the pressure exerted by the tooth 25 against face 40 will be about twenty pounds. Thus, lever 20 effects approximately a three to one reduction between the pressure exerted on lever 20 by bolt pin 23 and the pressure transmitted by lever 20 to detent 27. To disengage detent lever 27 from tooth 25 it is only necessary to overcome the frictional component of the twenty pounds force on the face 40. This disengaging force will depend on the smoothness and lubrication of faces 36 and 40, and will vary between four and eight pounds in accord with variations in these factors. As the door sealing pressure is increased up to a value of about three hundred pounds, it has been found by tests of the mechanism that the proportion of the transmitted force that is absorbed in friction increases rapidly so that the force required to release the detent lever 27 does not increase in proportion. At two hundred pounds seal pressure it may increase to only seven to ten pounds.

In view of the above it is evident that our lock is admirably adapted for operation either from within or from without the vehicle body by a push button or trigger release. As shown in Fig. 3, the door 2 is provided with a fixed outside handle 45 having a cylindrical opening 46 in which a push button 47 is arranged to slide inwardly and outwardly. Push button 47 is biased outwardly by compression spring 48. A conventional key controlled cylinder lock 49 is journalled in push button 47 and is provided with a conventional locking bar 50 which normally slidably engages handle 45 in groove 51 extending longitudinally in the wall of cylinder 46. When a key is inserted in cylinder barrel 49, locking bar 50 can be retracted out of groove 51 and cylinder 49 turned in a conventional manner to rotate shank 52 which is integral with lock cylinder 49. A shank extension 53 is fixed in the end of shank 52 so that lock cylinder 49, shank 52 and extension 53 rotate as a unit. A clamp 54 engages shank 52 in notches 55 and serves as a stop button for limiting outward movement of push button 47 and lock cylinder 49 under the influence of spring 48 and clamp 54 also serves to retain the lock cylinder and push button assembly within cylinder opening 46. Thus, it will be noted that push button 47, lock cylinder 49 and shank 52, 53, can be pushed inwardly and outwardly of cylindrical opening 46 as a unit and, in addition, lock cylinder 49 and shank 52, 53, when a key 54 is inserted therein to retract tumbler 50 from groove 51, can be rotated as a unit for purposes described below.

Our lock incorporates all the operative advantages of the lock shown in the Anderson-Bowlus Patent 2,039,873. For retracting the detent lever 27 from interengagement with either tooth 24 or 25 by means of push button 47 there is provided a channel guide member 56 (Fig. 13) provided with an opening 57 which receives pin 58 by means of which channel guide 56 is pivoted on lock frame 12 (Fig. 10). Channel member 56 is provided with a pair of side walls 59 having aligned openings 62 which receive pin 60 by means of which lever 61 is pivoted on channel guide 56. A hub 63 having a pair of spaced fingers 64 is journalled in lock frame 12 as at 65. Hub 63 is provided with a rectangular opening

56 which receives shank 53 since shank 53 is of corresponding rectangular cross section, rotation of shank 53 will rotate hub 63. Channel 56 is provided with a finger 67 which is located between fingers 64 so that rotation of hub 63 in one direction or the other will pivot channel 56 about pin 58. A slide bar 68 (Fig. 14) is provided with an elongated opening 69 and shoulders 70 and 71. Slide bar 68 is slidably mounted in channel guide 56 and is retained therein by pin 58 so that slide bar 68 also pivots with channel 56.

10 A lever return type spring 72 has one arm thereof anchored in slide bar 68 as at 73 and the other end anchored on lock frame 12 as at 74 (Figs. 5, 10). One end 75 of slide bar 68 is turned outwardly to form a shoulder against which lever 77 has an operative contact. The other end 76 of slide bar 68 slidably engages lever 77 between channel lips 78. Lever 77 is pivoted on frame 12 by pin 89 and is biased in one or the other of its positions by means of an over-center type spring 81 which has one end anchored to lever 77 and the other end anchored to lock frame 12. Link 82 extends through an opening in garnish molding 83 and is provided with a finger piece 84. The lower end of link 82 is pivotally connected to lever 77 as at 85. When finger piece 84 is raised, then lever 77 is swung to the position shown in Fig. 5 and slide bar 68 is raised or in unlocked position so that shoulder 71 will abut shoulder 86 on detent lever 27. Slide bar 68 and lever 77 will be biased in raised position by over-center type spring 81. If under such condition push button 47 is pushed inwardly (Fig. 3), shank 53 will swing lever 61 clockwise (Figs. 3 and 10) thus causing slide bar 68 to slide toward the left (Fig. 10) and shoulder 71 will act through shoulder 86 to swing detent lever 27 counterclockwise from the full line to the dotted line position Fig. 11, thereby releasing detent lever 27 from multiplying lever 26 so that the sealing pressure on the door, or any other outward force exerted on the door, will open the door and cause the bolt to swing to lowered position and travel out of channel 7 of striker plate 3. When push button 49 is released, spring 82 returns it to its normal position and spring 72 will return slide bar 68 to normal position, as shown in Figs. 5 and 9.

50 Since the lock is unlocked very easily and with a minimum of force by axial movement of shank 53 which acts through lever 61 and slide bar 68 to retract detent lever 27, it is obvious that any conventional finger or manually operated conventional mechanism can be located on the outside of the door for shifting shank 53 axially. By way of illustration, a push button 47 is shown for shifting shank 53 axially from without the door. This arrangement is preferred because the force applied on push button 47 is directly transferred to shank 53 without the need for any intermediate levers or links.

55 If finger piece 84 is pushed downwardly to swing lever 77 to the position shown in Fig. 9, then slide bar 68 will be in locked or free-wheeling position so that shoulder 71 is free to slide by shoulder 86 without contacting the same, as indicated by the dotted lines in Fig. 9. If at this time push button 47 is pushed inwardly, slide bar 68, which is now biased to locked position by spring 72, will simply slide freely by shoulder 86 and the push button 47 will be ineffective to release detent lever 27 and lock bolt 11 will remain in raised locked condition (Fig. 9) and interengaged with striker 3, as shown in Fig. 2.

5 It is evident that if key 54 is inserted in lock cylinder 49 so that locking bar 50 is retracted from groove 51, then by turning key 54 clockwise, as viewed in Fig. 5, hub 63 will be turned counterclockwise so that finger 64 will contact finger 67 and swing channel 56 and slide 68 to raised or unlocked position, as shown in Fig. 5. If key 54 is turned to rotate hub 63 clockwise (Fig. 9), then finger 64a, acting through finger 67, will swing channel 56 and slide 68 downwardly to locked or free-wheeling position (Fig. 9) so that push button 47 is now ineffective to retract detent lever 27.

15 For controlling slide bar 68 from within the vehicle we have provided a link 90 provided with an elongated opening 91 through which pin 28 passes so that link 90 is both slidable and rotatable upon pin 90. One end 92 of link 90 is arranged to contact shoulder 86 to release detent lever 27 when link 90 is drawn to the left (Fig. 9). Leftward movement of link 90 is accomplished by means of lever 93 pivoted on lock frame 12 by pin 94 and pivotally connected to link 90 by pin 95. A draft link 96 is pivotally connected at one end to lever 93 and the other end is pivotally connected to a lever 97 pivoted by pin 98 upon armrest 99 secured to the inside face of the door 2. Bell crank lever 97 is operated by push button 100 slidably mounted in recess 101 in armrest 99. A pin 102 passes through stem 103 of push button 100 to retain the same in opening 101. A compression spring 104 biases push button 100 outwardly. Pin 102 limits the outward movement of push button 100 so that it is always inset from the outer face 105 of armrest 99 so that push button 100 cannot be accidentally struck to release detent lever 27.

20 When the door is opened or detent lever 27 is released from lever 20, lock bolt 11, 16 will be in the position shown in Fig. 11 and bolt head 16 will be either in portion 7 of channel 6 or completely disengaged from striker channel 6. If the door is now swung shut, roller bolt 11 will travel up striker channel 6, as indicated by the arrow and dotted line showing Fig. 2. In travelling up striker channel 6, roller bolt 11 will be swung upwardly or counterclockwise, Figs. 11, 16, and safety tooth 24 will first cam detent lever 26 counterclockwise until tooth 26 interengages tooth 24 and at this time bolt 11 will be in safety position (Fig. 16) and the roller head 16 will be in the lower end of vertical portion 8 of channel 6. If the door is forced further inwardly, roller bolt end 16 will roll further up channel portion 8 of striker 3 causing tooth 25 to cam detent lever 27 upwardly or counterclockwise until tooth 26 interengages tooth 25 and the bolt is in fully locked position, Figs. 5, 17.

25 If, while bolt 11 is in released position and the door is open, Fig. 11, slide plate 68 is moved to locked position, Fig. 9, in the manner above explained, then as the door closes and bolt end 16 travels upwardly in striker channel 6, lever 20 will swing counterclockwise, Fig. 11, and tooth 24 will cam lever 27 counterclockwise to the dotted line position shown in Fig. 11, whereupon shoulder 106 of lever 27 will contact shoulder 70 of slide bar 68 and pivot slide bar 68 from the locked position, shown in Fig. 9, to the unlocked position, shown in Figs. 5 and 15, so that shoulder 71 will now contact shoulder 86 if slide 68 is moved to the left.

30 If one wishes to lock the door without using key 54, as above described, this can be accom-

plished by pushing finger piece 84 downwardly while the door is open which, as above explained, shifts slide bar 86 to locked or free-wheeling position, shown in Fig. 9. If the operator, while the door is still open, will now push inwardly on push button 47, which acts through shank 53 and lever 61 to shift slide bar 68 to the left or dotted line position shown in Fig. 9, then shoulder 70 will be to the left of shoulder 106 and as lever 27 is swung upwardly or counterclockwise by teeth 24 and 25, shoulder 106 will not abut shoulder 70 but will pass freely by shoulder 70 and consequently slide bar 68 will remain in lowered or locked position, full line showing Fig. 9. In thus locking the door without the use of key 54 the operator, owing to this unusual procedure, will be reminded to first remove the ignition keys from the ignition lock.

Inasmuch as the sealing pressure in the modern automobile is considerable, as a practical matter the door will be closed by slamming the same shut. If the door is only closed to safety position (Fig. 16) while locking the same without a key, then the operator need merely release push button 47 and push on the door whereupon the action of the striker plate through bolt 11 and lever 20 will cause tooth 25 to cam lever 27 upwardly which, as above explained, will raise slide bar 68 to unlocked position. The door can now be opened by pushing in on push button 47 and is now ready to be again closed and locked without a key, as above described. Thus, even if the door does close only to safety position, the operator still can fully close and lock the door without use of the key 54.

In the modified form of our invention bolt 11 cooperates with the same type of striker plate, as shown in Fig. 2. Bolt 11 is connected to a multiplier lever 110 by means of pin 111 which slidably engages lever 110 in elongated slot 112. Lever 110 has a single tooth 113. Lever 110 is pivoted on lock frame 12. For holding the bolt in raised or locked position we have provided a safety detent lever 115 pivoted on frame 12 by pin 116 and having a finger 117 for interengagement with tooth face 114 when bolt 16 is in safety position. A second detent lever 118 is pivoted on lever 115 by pin 119. Coil spring 120 has one end anchored on pin 116 and the other end anchored to detent lever 118 and biases lever 118 in a clockwise direction (Fig. 19). Detent lever 118 has finger 121, the inside face 122 of which is arcuate as in the principal form of the invention. Face 114 of tooth 113 is also arcuate and faces 114 and 122 are arcs having equal radii with their centers at the axial center of pin 119 about which detent 118 swings so that face 122 can be released from face 114 easily as described above with respect to the principal form of the invention.

A plate 123 is provided with an elongated slot 124 in which it slidably engages a stud 125 fixed on lever 115. Plate 123 is connected by link 96 with the inside push button as above described. Movement of plate 123 toward the left (Fig. 19) acts through stud 125 to swing detent lever 115 counterclockwise and at the same time detent 118 is swung about pin 116 as a center to thereby release tooth 114 of lever 110 from finger 121 to thereby release lock bolt 11. Detent lever 121 has a finger 126 which overlies edge 127 of lever 115 so that detent lever 118 will always swing bodily with lever 115. Lever 115 can be swung from without the vehicle by push button arrangement identical with that described above.

The shank 53 of the push button arrangement, however, acts upon a modified form of mechanism which comprises a lever 130 pivoted to swing about a vertical axis upon pin 131 which is mounted upon two flanges 132 integral with lock plate 12. Flanges 132 also serve as a guide for one end of slide bar 133 and the other end of slide bar 133 is provided with an elongated opening 134 for rivet pin 135 which is fixed to lock plate 12. A lever 136 is pivotally supported on bar 133 by rivet pin 137. Lever 136 has one end bifurcated as at 138. Bifurcated end 138 of lever 136 receives pawl 139 which is integral with hub 140 which in turn is rotated by shank 53 as in the principal form of the invention. Lever 136 has a shoulder 141 which is arranged to cooperate with shoulder 142 turned out of lever 115. Left hand end 144 of lever 136 is mounted between outwardly turned fingers 145 on lever 146 pivoted by pin 135 upon plate 12. Spring 147 has one end anchored on pin 135 and the other end anchored to lever 146 between fingers 145 so that spring 147 acts as an over-center spring to bias levers 146 and 136 in either locked or unlocked position. Lever 146 can be actuated by a finger piece in the garnish molding through a link 82 in the same manner as described above for the principal form of the invention.

When lever 136 is in unlocked position, as shown in Fig. 19, with shoulder 141 abutting shoulder 142 of lever 115, the detent lever 115 can be released either by operation of the inside push button 108 or the outside push button 47. Further, lever 136 can be set in locked or unlocked position either from the inside by operation of the finger piece 84 or from the outside by turning key 54 which acts through shank 53 and pawl 139 and bifurcated end 138 of lever 136 to swing it to either locked or unlocked position. Detent lever 115 has a pin 150 fixed thereon which projects into opening 151 in lever 115. The upper edge of opening 151 is sinuous and comprises humps 152 and 153 and valleys 154 and 155. Lever 115 also has a lug 156 struck inwardly toward plate 12 at right angles to the general plane of lever 115. Lug 156 is located so that when lever 136 is in lowered or free-wheeling position the lower edge 157 abuts the upper edge of lug 156. Hence, if lever 136 is in lowered or locked position (Fig. 20), when the vehicle door is open and bolt 11 is in lowered position, then upon closing the door the striker plate swings bolt 11 upwardly which, through pin 111, rotates lever 110 counterclockwise and pin 150 on lever 110 slidably engages hump 152 and swings lever 115 upwardly or counterclockwise which, through lug 156, acts against lower edge 157 of lever 136 to return lever 136 to unlocked position (Fig. 19).

This lock can be locked without the use of key 54 in the same manner as above described. Here again if, while locking the door without the key, the door should engage the striker in safety position, then, as shown in Fig. 23, pin 150 will be located in recess 154. Here again the operator simply releases push button 47, pushes inwardly on the door and pin 150 will cooperate with hump 153 to pivot lever 115 and thereby raise or swing lever 136 to unlocked position so that the door can be reopened, the lock reset to locked position by pressing down on finger piece 84, and then swung shut while holding push button 47 inwardly. In this condition, as bolt 16 rides up the striker, lug 156 misses the right hand end of edge 157 of lever 136 and simply swings freely

upwardly in corner 158 without resetting lever 136 to unlocked position.

We claim:

1. In a door lock, a bolt shiftable from unlocked position to locked position and from locked position to unlocked position, a detent, and a lever having one arm operatively associated with said lock bolt so that movement of said lock bolt swings said lever about its fulcrum, a spring urging said detent toward said lever, the other arm of said lever having a tooth provided with a cam surface, movement of said lock bolt from unlocked to locked position causing said cam surface to cam said detent outwardly until said cam surface clears said detent whereupon said spring moves said detent into interengaged relation with said tooth and said detent acts through said lever to retain the bolt in locked position, the first mentioned arm of said lever being shorter than the second mentioned arm whereby any force exerted by said bolt in an unlocking direction against said first mentioned lever arm produces a substantially lesser force acting through said longer arm against said detent.

2. In a door lock, a lock frame, a bolt pivotally mounted on said frame and shiftable from unlocked position to locked position and from locked position to unlocked position, a detent pivotally mounted on said frame, a lever pivoted on said frame having arms of unequal length, said detent being swingable into and out of interengagement with said lever, a spring urging said detent toward said lever, an operative contact between the shorter arm of said lever and the bolt, said pivotal connection being located radially outwardly from the axis of said lever, whereby shifting of said bolt causes said lever to pivot about its fulcrum, the other arm of said lever having a tooth provided with a cam surface, the shifting of said bolt from unlocked to locked position causing said cam surface to cam said detent outwardly until said cam surface clears said detent whereupon said spring moves said detent into interengaged relation with said tooth whereby the detent blocks return shifting of the bolt to unlocked position.

3. The combination as set forth in claim 2 wherein the fulcrum of the bell crank lever is positioned between the pivot of the bolt and the contact between the short arm of the lever and the bolt.

4. In a door latch comprising a lock frame and a movable latch member thereon, means for releasing said member comprising a channel guide member pivoted on said frame to swing into either of two positions, said channel guide having side walls, a lever pivoted on the side walls of said guide to swing about an axis transverse of the axis about which said guide swings, a bar mounted upon, and guided for longitudinal movement along said channel guide, said bar having an operative contact with said latch member in the first of said positions of said channel guide and being operatively out of contact with said latch member in the second position of said channel guide, an operative contact between said lever and bar whereby pivoting movement of the lever on said channel guide in one direction moves said bar longitudinally along said guide to projected position to release said bolt when the guide is in the first of its pivoted positions, said bar being ineffective to release said latch member when the guide is pivoted to its second position.

5. The latch defined in claim 4 including resil-

ient means acting on said bar for retracting the same.

6. In a latch mechanism for a swinging door, a frame, a latch member pivotally mounted on said frame and movable into latched position for holding the door closed and movable to released position to permit opening the door, a guide member pivoted on said frame to swing into either of two positions about an axis substantially perpendicular to the plane of said frame, a bar mounted on, and guided by, said guide to pivot with said guide and to shift longitudinally on said guide, said bar having an operative contact with said latch member in the first of said positions of said channel guide and being operatively out of contact with said latch member in the second position of said channel guide, a lever pivotally mounted on said guide to swing about an axis substantially perpendicular to the axis of pivoting of said guide, said lever having an operative contact with said bar whereby when the lever is swung about its pivot on said guide the bar bodily shifts said bar along said guide to release said latch member when the guide is in its first position, said bar being ineffective upon longitudinal movement to release said latch member when the guide is pivoted to its second position, and manually operable means for swinging said guide about its axis into one or the other of said positions.

7. The latch defined in claim 6 including a push member manually operable from without the door and shiftable in a direction parallel to the axis of pivoting of said guide member for swinging said lever to thereby shift said bar.

8. The latch defined in claim 7 including a hub journalled in said frame to swing about an axis parallel to the axis of pivoting of said guide and having an operative contact with said guide whereby turning of said hub pivots the guide to one or the other of its positions.

9. The latch defined in claim 8 wherein said hub is provided with an axial opening, said push member passing through said axial opening and being axially slidable therein and having an operative contact with said lever whereby said push member can be actuated to pivot said lever about its axis and project said bar, a driving contact between said push member and hub whereby turning of said push member pivots said guide to one or the other of its said positions.

10. In a door latch comprising a latch frame and a retractable latching member, a channel guide having a bottom and side walls, a pin pivotally interconnecting the latch frame and the bottom wall of said channel guide with the side walls of the channel positioned in a plane substantially perpendicular to that of the latch frame, a lever, a pin mounted on the side walls of said channel guide for pivotally supporting the lever on said channel guide to swing about an axis substantially perpendicular to the axis about which the channel guide member swings, a bar mounted upon and guided for longitudinal movement along said channel guide, said lever having an operative contact with one end of said bar whereby pivoting of said lever in one direction projects said bar, resilient means acting upon and tending at all times to retract said bar and lever, and means for swinging said channel guide member and bar to operative and inoperative positions, said guide bar when in operative position having an operative contact with said latching member whereby projecting movement of the bar retracts said latching member, said latch bar

when in inoperative position being out of operative contact with said latching member whereby projecting movement of the bar is ineffective to retract the latching member.

11. The latch defined in claim 10 including a hub journaled on said frame to swing about an axis parallel to the axis of pivoting of said guide, cooperating fingers on said channel guide and hub whereby turning of the hub pivots the guide to operative or inoperative position.

12. The latch defined in claim 11 wherein the hub is provided with an axial opening, a push member passing through said axial opening in the hub and being axially slidably therein, said push member having a driving contact with said lever whereby the push member can be actuated to swing said lever and project said bar, and a driving contact between said push member and hub whereby turning of said push member acts through said hub to pivot said guide to operative or inoperative position.

JAMES D. LESLIE.
CLYDE H. SCHAMEL.
